UNITED STATES PATENT OFFICE.

FREDERICK J. JACKSON, OF TARRYTOWN, AND WILLIAM H. WRIGHT, OF SAUGERTIES, NEW YORK.

WASH-BOILER.

SPECIFICATION forming part of Letters Patent No. 231,584, dated August 24, 1880.

Application filed June 21, 1880. (No model.)

To all whom it may concern

Be it known that we, FREDERICK J. JACKSON and WILLIAM H. WRIGHT, citizens of the United States, residing, respectively, at Tarrytown and Saugerties, in the State of New York, have jointly invented a new and useful Improvement in Wash-Boilers, of which the following is a specification.

This invention relates to what are known as "fountain wash-boilers;" and it consists in a novel fountain device of simplicity and efficiency, operating by the expansion of heated water between an inclined shelf and the bottom of the boiler-pit and between said shelf and a top plate; also, in a novel form of inlet and a novel form of outlet for a fountain-chamber at or within the bottom of a boiler and its pit, as hereinafter more fully set forth.

In the accompanying drawings, which form a part of this specification, Figure 1 is a plan view of a wash-boiler bottom illustrating this invention. Fig. 2 is a like view of the same without its top plate. Fig. 3 is a longitudinal section on the line 3 3, Fig. 1, showing the complete device as combined with a boiler-body and with a discharge pipe or neck within the latter; and Fig. 4 is a cross-section on the line 4 4, Fig. 3.

Our wash-boiler may have a body, A, a bottom, B, and a cover, C, of ordinary make. The bottom B must, however, have a long deep pit, D, adapted to occupy the boiler-hole of a stove or range in customary manner, and to afford space within it for our principal attachment E, which is an inclined plate or shelf extending across the pit D from side to side and longitudinally from one end, which is its highest point, to a point near the opposite end, where a space, s, is left for the entrance of the water into the space or fountain-chamber s² beneath said shelf.

An outlet-extension, o, formed on the higher end of the shelf E, projects upward and over the marginal floor of the bottom B, and terminates in a collar, which receives the discharge pipe or neck n, and locates the latter near the extreme end of the bottom, as shown. The bottom of the elevated outlet beyond the end of the pit is formed, in a simple manner, by said marginal floor, as shown in Figs. 3 and 4.

In use, the entire internal area of the bottom of the pit D being utilized for heating the water beneath the shelf E, this water is quickly raised to boiling heat, causing it by its expansion and ebullition to pour through the outlet o and neck n upon the articles within the boiler, so as to wash the same by the now well-known process. Said shelf E, forming the single fountain-chamber s², will operate as above described when used alone or exposed, as shown in Fig. 2, and it may be so used with the additions of the customary supporting-rack to prevent choking. The action is, however, rendered greatly more energetic and effective by the addition of a top plate, F, having an inlet or inlets, i, at the end opposite said space s. A preliminary heating space or chamber, s', is thus formed above the shelf E, and the water therein receives sufficient heat through said shelf and through the sides of the pit to expand into the chamber s² with its temperature already considerably increased, and the inclination of the shelf D prevents retrogression in both chambers.

The inlets i are formed at the sides of the outlet o by means of an elevated end of the top plate, F, supported by stud-pins p, which project from the said marginal floor of the bottom B, as shown in Fig. 2, and form efficient strainers to preclude the entrance of small articles into the fountain-chambers, as shown in Fig. 4.

The shelf E and top plate, F, should be soldered within the pit D and to the floor of the bottom B, so as to render their edges watertight. Depending projections or beads x x² are formed on the top plate to facilitate locating it preliminary to soldering it down.

The bottom B, with the pit D, stud-pins p, stiffening-ribs r r, and an elevated marginal flange, f, to unite with the body, and the shelf E, with the outlet o thereon, are, by preference, light galvanized-iron castings, but may be made of suitable sheet metal by ordinary processes.

The top plate, F, owing to its simple form, may preferably be made of sheet metal cut and bent to the form shown; but it may also be cast, and in either case it may itself be provided with the stud-pins p, or equivalent pro-

jections; and to facilitate casting it sufficiently light it may be made in two or more sections united by solder.

As thus and in like manner modified in un-
5 essential details the attachments E F may be
readily fitted to an ordinary wash-boiler bot-
tom having a suitable pit, and they may be
further modified by employing simple inlet and
outlet orifices guarded and finished in any pre-
10 ferred manner without materially affecting
their operation, as above stated.

We do not, therefore, limit ourselves in these
particulars. Our superior inlet and outlet may
also be applied in substance to other fountain
15 wash-boiler bottoms.

We do not claim herein, broadly, a wash-
boiler having a pit adapted to project into and
fill, or nearly fill, the boiler-hole of a stove or
range, and provided with a top plate and a par-
20 tition or partitions forming fountain-cham-
bers, as we intend to claim this in another ap-
plication for patent, which will be filed here-
after.

We claim as new and of our joint invention
25 and desire to protect by Letters Patent—

1. In a wash-boiler, a bottom having a pit
provided with an inclined longitudinal shelf
extending across the pit from side to side, and
forming a shallow fountain-chamber immedi-
30 ately above the bottom of the pit, a space for

the admission of water to said chamber at
the lower end of said shelf, and an outlet for
the heated water at the higher end of said
shelf, and a top plate forming an inlet or in-
lets at said higher end only of the shelf for 35
the admission of water to said space, substan-
tially as herein specified, for the purposes set
forth.

2. In a wash-boiler, a sunken bottom having
a fountain-chamber within its pit or depres-
sion, and provided with a top plate having an
elevated end forming an inlet or inlets to said
chamber and supported by stud-pins which
40 form strainers at said inlets, substantially as
herein described.

3. In a wash-boiler, a sunken bottom having
a fountain-chamber formed within its pit or
depression, and provided with an elevated out-
let projecting over the marginal floor of said
bottom, the bottom of said outlet being formed 5
in part by said marginal floor, while the termi-
nal collar of the outlet receives a discharge-
neck and locates the latter near the extreme
end of the boiler, substantially as herein speci-
fied, for the purposes set forth.
